FIREPLACE SCREEN

Adolph R. Murat, San Clemente, Calif.

Application October 9, 1950, Serial No. 189,203

5 Claims. (Cl. 160—298)

1

The present invention relates to new and useful improvements in fireplace screens and more particularly to a screen roller for raising and lowering the screen and providing foot treadle operating means for the roller whereby the screen may be raised by the foot of a person while the hands are free to place logs on the fire.

An object of the invention is to provide a foot operated mechanism for raising and lowering the screen and including a brake mechanism for automatically holding the screen in raised position while the fire is being supplied with fuel or the fireplace is being cleaned.

Another object is to provide a device of this character of simple and practical construction, which is efficient and reliable in operation, neat and attractive in appearance, relatively inexpensive to manufacture and otherwise well adapted for the purposes for which the same is intended.

Other objects and advantages reside in the details of construction and operation as more fully hereinafter described and claimed, reference being had to the accompanying drawings forming part hereof, wherein like numerals refer to like parts throughout, and in which:

Figure 1 is a perspective view;

Figure 2 is an enlarged longitudinal broken sectional view of the roller for the screen taken substantially on the line 2—2 of Figure 1 and showing the rope and pulley operating means therefor;

Figure 3 is an enlarged vertical sectional view taken on a line 3—3 of Figure 1;

Figure 4 is an enlarged fragmentary vertical sectional view taken on a line 4—4 of Figure 3;

Figure 5 is an enlarged fragmentary sectional view taken on a line 5—5 of Figure 4;

Figure 6 is an enlarged fragmentary sectional view taken on a line 6—6 of Figure 4; and

Figure 7 is an enlarged fragmentary sectional view taken on a line 7—7 of Figure 1.

Referring now to the drawings in detail, wherein for the purpose of illustration I have disclosed a preferred embodiment of my invention, the numeral 5 designates a fireplace screen of flexible foraminous or other suitable material for winding on a roller 6 having a shaft 7 journaled in bearings 8 in a horizontal housing 9 secured in front of the upper portion of a fireplace 10. One edge of the screen travels in a guide channel 11 at one side of the fireplace, while the other edge of the screen travels in a guide channel 12 at the side of a vertical housing 13 which extends downwardly from one end of horizontal housing 9.

A drum 14 in the housing 9 is keyed on one

2

end of shaft 7 for winding a cable 15 thereon and which has one end extending downwardly around a pulley 16 and attached to the upper portion of housing 13. Pulley 16 is rotatably mounted at the upper end of a bar 17 which is slidable in a vertical guide 18 secured in vertical housing 13 and a foot pedal or treadle 19 is secured to the lower end of bar 17 by means of a web 20 which slides in a vertical slot 21 in the front of vertical housing 13 to position the treadle forwardly thereof.

A brake drum or disk 22 is integrally formed with or otherwise suitably fixed to drum 14 and with the periphery of which a wedge shaped 15 brake 23 is engageable. Brake 23 is slidable vertically in housing 9 between the front wall of the housing and the brake drum and is pulled upwardly into braking position by a contractile coil spring 24. A brake releasing lever 25 is pivoted on shaft 7 and projects outwardly into a position in front of housing 9 through a vertical slot 26 in the housing 9. A pin 27 projects laterally from one side of brake 23 into a slot 28 in lever 25 to connect the lever to the brake to release the brake by sliding the latter downwardly.

In the operation of the device a weighted strip 29 is attached to the lower end of screen 5 and by releasing brake 23 the weight of screen 5 unrolls the screen, or the screen may be pulled downwardly into its lower position to close the fireplace. In this position the treadle 19 is pulled upwardly by cable 15 which winds on drum 14 as the screen is lowered, and by stepping on the treadle the roller is rotated in a direction to raise the screen. During the raising movement of the screen the brake drum 22 is rotated in a direction tending to release brake 23 to prevent binding action between the brake and brake drum.

In view of the foregoing description taken in conjunction with the accompanying drawings it is believed that a clear understanding of the construction, operation and advantages of the device will be quite apparent to those skilled in this art. A more detailed description is accordingly 45 deemed unnecessary.

It is to be understood, however, that even though there is herein shown and described a preferred embodiment of the invention the same is susceptible to certain changes fully comprehended by the spirit of the invention as herein described and the scope of the appended claims.

Having described the invention, what is claimed as new is:

1. A fireplace screen comprising a roller on which a screen is mounted for raising and lower-

ing movement, foot pedal operated means for rotating the roller in a direction to raise the screen, braking means for the roller, and spring means holding the braking means in brake applying position, said braking means being released upon turning of the roller in a direction to raise the screen.

2. A fireplace screen comprising a roller on which a screen is mounted for raising and lowering movement, a drum connected to the roller, a cable on the drum, a foot pedal connected to the cable for rotating the drum in a direction to wind the screen thereon, a brake drum on the first named drum, a sliding brake, spring means holding the brake in engagement with the brake drum, and lever means connected to the brake to release the latter.

3. A fireplace screen comprising a roller on which a screen is mounted for raising and lowering movement by rotation of said roller in opposite directions, respectively, a vertical guide, a foot pedal vertically slidable in said guide, and operating connections between said pedal and roller rotating said roller in one direction upon downward sliding of said pedal.

4. A fireplace screen according to claim 3 in-

cluding a weight on said screen tending to lower the screen and rotate said roller in the other direction, said operating connections sliding said pedal upwardly upon rotation of said roller in said other direction to position the pedal for downward sliding.

5. A fireplace screen according to claim 3 wherein said operating connections comprise a drum on said roller, a pull cable forming a loop with one end wound on said drum and the other end thereof anchored in fixed position, and a bar carrying said pedal and having a pulley thereon working in said loop.

ADOLPH R. MURAT.
